United States Patent Office.

HENRY A. GASTON, OF STOCKTON, CALIFORNIA.

Letters Patent No. 78,080, dated May 19, 1868.

IMPROVEMENT IN CULTIVATORS.

The Schedule referred to in these Letters Patent and making part of the same.

TO ALL WHOM IT MAY CONCERN:

Be it known that I, HENRY A. GASTON, of the city of Stockton, county of San Joaquin, and State of California, have invented an Improvement in Cultivators; and I do hereby declare that the following, taken in connection with the drawings, which accompany and form part of this specification, is a description of my invention, sufficient to enable those skilled in the art to practise it.

The invention relates particularly to the construction of bits or cultivator-teeth, with reference to applying them to the standards which support them, and connect them to the cultivator-frame or carriage, and to the construction of the standards with reference to such connection.

The drawings represent a cultivator embodying my improvements.

A shows a bottom view of the same.

B a side elevation thereof.

C is a detail view of one of the standards, showing the bit in section.

D is an edge view of the standard.

E is a plan of the bit.

F and G show modifications of the devices for connecting the bit to the standard.

a denotes a cultivator-frame, constructed and mounted on wheels b in any suitable manner.

From this frame depends a series of vertical iron standards, c; (to the foot of which the cultivator-tooth or bit d is fixed,) the top of each standard extending through the cultivator-beam, such top having a screw-shank, upon which a nut, e, is screwed, to fasten the standard to the beam, the standard also having, if necessary, a brace, f extending rearwards and upwards to the frame, this brace receiving the back strain upon the standard.

The cultivator-bits d are of that class of bits which are made reversible, that is to say, the two ends of each bit are alike, as are also the upper and lower surface of each, so that each bit may be reversed end for end, or top for bottom, thus making of each not only a double bit, but a self-sharpening bit or tooth, the edge being kept sharp by turning the bit and using the upper and lower surfaces interchangeably.

The principal object of my invention is to make a perfectly strong and rigid connection of the bit to the standard, by simple means, that admit of easy and quick change or adjustment of each bit, without the exercise of other than the most ordinary skill.

Each bit stands at an inclination with reference to its standard, as seen at B, and through the centre of each, a mortise, g, is formed, through which mortise a tenon, h, on the foot of the standard projects, as seen at A and C, the tenon and mortise being made narrower than the standard, the top of the bit resting against the shoulder i, formed at the juncture of the tenon and standard.

One end of the tenon is shown as formed with a recess or slot, m, into which the bit slips, (at the adjacent end of the bit-slot,) as seen at C.

In the standards shown at C, the tenon from front to rear is of a length corresponding to the length of the bit-mortise, so that the tenon will just slip through the same. When so slipped through, however, the bit is moved back into the slot m, and this leaves a space, l, between the rear of the standard and the rear side of the bit-mortise. Into this hole or space l, a key is driven, and the bit is thereby firmly secured from displacement, excepting by removal of the key, the key keeping the bit from end movement, and the key and slot and shoulder i keeping it from vertical movement.

When any bit needs to be turned end for end or top for bottom, the key is driven out and the bit slipped forward, when it will readily fall from the standard.

Instead of having the slot m in the tenon, the tenon may be formed to just fit the bit-mortise, as shown at E, the bit being confined by a screw-bolt and a washer, the bolt entering the bottom of the tenon, its head bearing upon the washer, and holding it tight against the bit, the washer being made large enough to overlap the tenon; or the head of the bolt may itself be made to so overlap. In this modification the standard is preferably made with an extension or brace, n, for the bit to bear against. Or the slot or recess m may be made in the form shown at F, the bit having a corresponding projection, o, at each end of its mortise, to fit

into such recess, the bit being held either by a key, as shown at C, or by a screw-bolt or bit and washer, as shown at E.

I claim, in combination with an inclined reversible bit for a cultivator, the method of securing such bit to its standard, substantially as set forth.

I also claim the combination of the series of bits (so applied to their vertical standards) with the cultivator-frame or carriage, substantially as described.

HENRY A. GASTON.
